UNITED STATES PATENT OFFICE

2,590,727

SELF-CONTAINED ROTARY DEVICE

Frank Scognamillo, Bronx, N. Y., assignor to
 Scognamillo Engineering Company, Bronx,
 N. Y.

Application February 21, 1949, Serial No. 77,649

2 Claims. (Cl. 103—136)

1

This invention relates to rotary devices particularly of the self-contained rotary pump, engine, or compressor type, and in particular a rotary device having a dual blade such as a blade having a smaller blade contained therein and resiliently urged outwardly for wiping contact with the inner peripheral surface of a cylindrical pump chamber, and wherein a rotor in which the blade is positioned is journaled on a core eccentrically positioned in the pump chamber and extended from one end of the housing cover continuously through the rotor.

The purpose of this invention is to provide an improved type of construction for rotary devices wherein a blade driven by a driving flange on a power actuated shaft drives a rotor in which the blade is positioned around a shaft or core which is stationary in the device.

This invention is an improvement over the blade driven rotary pump of a former application of my father, Salvatore Scognamillo, deceased, which application was filed December 18, 1948, with the Serial Number 66,098, and also on a copending application filed June 16, 1948, with the Serial Number 33,407, and furthermore of a pump of the prior Patent Number 2,443,994; the above copending applications and patent having been assigned to the Scognamillo Engineering Company, to which the application is also assigned by an assignment filed herewith. The improvements of this invention being in that the shaft extends continuously through the device and rotor, and the rotor is journaled on a shaft formed by a core extended inward from an end of the housing, and the blade provides a cradle for an auxiliary inner blade providing a blade within a blade and with the blade forming the cradle held by a floating and traveling ring and flange through extending pins having cylindrical heads.

A further improvement contemplated in this invention is in the novel construction and adaptation of a dual blade in that the auxiliary blade is self-contained therein and in continuous contact against the surface of the surrounding housing free from the reciprocal action of the outer blade positioned in the rotor slot.

In the usual type of rotary device such as a pump, engine, compressor, or the like the blade or blades slide in and out of a rotor fixed on or integral with a shaft, and in the improved device of the above-noted application where the rotor is free or floating the rotor is carried by a comparatively small pin which provides a limited bearing surface. With this thought in mind this improved device provides a relatively large sta-

tionary core which extends through the rotor and on which the rotor is freely slideable, and with the parts arranged in this manner it is possible to extend the driving shaft straight through the device with bearings at both ends.

The object of this invention is, therefore, to provide an improved type of construction for rotary devices wherein a floating rotor is journaled on a large core or shaft and wherein the shaft extends through the rotor.

Another object of the invention is to provide a rotary device having a dual self-contained blade wherein an inner blade is carried by a larger blade which provides a cradle or carrier for the small inner blade.

Another object of the invention is to provide a rotary device wherein a floating rotor is rotated by a blade or a plurality of blades in which the blades are actuated by a driving flange through longitudinally slideable pins with cylindrical heads, and wherein the heads of the pins in the opposite ends of the blades are positioned in sockets in a floating ring.

A further object of the invention is to provide an improved rotary device having dual blades with pins having cylindrical heads and a rotor journaled on a stationary core which is of a comparatively simple and economical construction.

With these ends in view the invention embodies a rotary device having a housing with inlet and discharge connections in which a dual blade is positioned in a slot in a rotor journaled on an eccentrically positioned stationary core through which a driving shaft extends and the rotor is actuated by the blade which is driven by a driving flange keyed to the driving shaft.

Other features and advantages of the invention will appear from the following description taken in connection with the drawings, wherein:

Figure 1 is a view showing an end elevation of the housing of the device with the cover plate and core removed and with parts shown in section.

Figure 2 is a longitudinal section through the device with the blade shown in elevation.

Figure 3 is a longitudinal section through the dual blade.

Figure 4 shows an end elevation of the blade.

Figure 5 is a cross sectional view of a modified form of blade wherein an inner blade is replaced by a wearing or wiping strip.

Figure 6 is an end view of the cylindrical head and pin of one end of the blade.

Figure 7 is a view showing a side elevation of the pin and head.

Figure 8 is a longitudinal section similar to that

shown in Figure 2 showing the housing and core with the moving parts removed.

Figure 9 is an elevational view of the cover plate and core with part broken away.

Figure 10 is a cross section through the driving flange.

Figure 11 is an end elevation of the driving flange.

Figure 12 is an end elevational view of the floating ring.

Figure 13 is a cross section through the floating ring.

Figure 14 is a longitudinal section through the rotor on a slightly reduced scale.

Figure 15 is a similar view showing a modification wherein the intermediate part of the rotor is cored away.

Referring now to the drawings wherein like reference characters denote corresponding parts the self-contained rotary device of this invention includes a housing 10 made up of opposed end walls, one of these the cover plate 11, connected by a cylindrical peripheral wall forming with the end walls a substantially cylindrical chamber, with a driving shaft 12, a rotor 13, a driving flange 14, a blade 15, providing a cradle, and a floating ring 16, and wherein the floating ring is journaled on a hub 17 on the inner surface of the cover plate and the rotor is journaled on a core 18 extended from the hub of the cover plate.

The housing is provided with a hub 19 and a similar hub 20 is provided in the cover plate which is bolted to the housing by bolts 21 and the shaft 12 is journaled in these hubs which are aligned as shown in Figure 2. The shaft also extends through and is journaled in the core 18, and the driving flange 14 is mounted on the shaft and secured in position thereon by a key 22 that extends into a keyway 23 in the flange. The hub 19 is provided with an annular recess 24 in which the hub 25 of the driving flange is positioned.

The dual blade 15 is formed with a longitudinal slot 26 and a bore 27, as shown in Figures 3 and 4, and a wiper or inner blade 28 is positioned in the slot and resiliently held outwardly by springs 29 and 30, which are held against ledges 31 and 32, respectively. It will be understood that springs of any other type or design may be used and also that the blade may be urged outwardly by any other suitable resilient means. The blades are provided with pins 33 having cylindrical heads 34, the pins being free to turn and slide lengthwise in the bore 27, and the head at one end of the blade being positioned in an opening 35 in the driving flange 14 with the head at the opposite end positioned in an opening 36 of the floating ring 16.

The rotor 13 is provided with a bore 37 to receive the core 18, and a slot 38 in which the cradle or dual blade 15 is positioned, and in the design shown in Figure 15, the intermediate part of the rotor 39 is removed providing a recess 40 with flanges 41 and 42 at the ends of the rotor, which is also provided with a bore 43 and a slot 44 for a blade.

A further modification is illustrated in Figure 5 wherein a blade 45 is provided with integral cylindrical heads 46 at the ends that fit into the openings 35 and 36 of the driving flange and floating ring respectively, and this blade is provided with a wiping strip 47 that contacts the inner peripheral surface 48 of the rotor chamber 49 in which an open crescent-shaped area 50 is provided, as shown in Figure 1.

With this improved type of construction the

rotor, which is in the form of a sleeve travels freely around a fixed or stationary core which is part of the housing and this provides a continuous crescent area through which the blade or blades are driven, and with the cylindrical heads at the ends of the blade free to slide longitudinally of the blade any unevenness of the parts is compensated for and smooth and balanced operation is assured.

10 This construction is not only adapted for pumps, engines and compressors, but may also be used for other types of machinery, such as ventilators, blowers, turbines, fluid couplings and fluid drives, and the like.

15 It will also be understood that modifications may be made in the design and arrangement of the parts without departing from the spirit of the invention:

What is claimed is:

20 1. A rotary machine of the character disclosed comprising a housing having opposed end walls connected by a cylindrical peripheral wall and forming therewith a substantially cylindrical chamber, said peripheral wall having spaced inlet and outlet ports open to said chamber, a shaft journaled in said end walls concentric with said cylindrical chamber, a cylindrical flange fixed on said shaft at the inner face of one of said end walls and having a cylindrical socket in the peripheral portion of the same open to said chamber, a cylindrical ring journaled on said opposite end wall concentric to said chamber and having a cylindrical socket in the peripheral portion of the same opposed to said socket in the flange, a stationary cylindrical core projecting from said opposite end wall to the inner face of said flange, a cylindrical rotor journaled on said core eccentric to said chamber and in running engagement with the peripheral wall between said ports, said rotor extending full length between said flange and ring and having a substantially radial slot in the periphery of the same and a blade slidably engaged in said slot and having running clearance with said peripheral wall, said blade having cylindrical heads at the opposite ends of the same rotatably engaged in said sockets in the flange and ring, respectively.

2. A rotary machine of the character disclosed comprising a housing having opposed end walls connected by a cylindrical peripheral wall and forming therewith a substantially cylindrical chamber, said peripheral wall having spaced inlet and outlet ports open to said chamber, a shaft journaled in said end walls concentric with said cylindrical chamber, a cylindrical flange fixed on said shaft at the inner face of one of said end walls and having a cylindrical socket in the peripheral portion of the same open to said chamber, a cylindrical ring journaled on said opposite end wall concentric to said chamber and having a cylindrical socket in the peripheral portion of the same opposed to said socket in the flange, a stationary cylindrical core projecting from said opposite end wall to the inner face of said flange, a cylindrical rotor journaled on said core eccentric to said chamber and in running engagement with the peripheral wall between said ports, said rotor extending full length between said flange and ring and having a substantially radial slot in the periphery of the same and a blade slidably engaged in said slot and having running clearance with said peripheral wall, said blade having cylindrical heads at the opposite ends of the same rotatably engaged in said sockets in the flange

and ring, respectively, said heads at the ends of the blade comprising pins rotatably and slidably engaged in the ends of the blade and having enlarged cylindrical end portions engaged over the ends of the blade.
